The ornamental design for a nozzle ring, as shown and
described.

DESCRIPTION

FIG. 1 is a front perspective view of an ornamental design
for a nozzle ring according to the invention.

FIG. 2 is a right view the nozzle ring of FIG. 1.

FIG. 3 is a left view of the nozzle ring of FIG. 1.

FIG. 4 is a top view of the nozzle ring of FIG. 1.

FIG. 5 is a bottom view of the nozzle ring of FIG. 1.

FIG. 6 is a back view of the nozzle ring of FIG. 1.

FIG. 7 is a front view of the nozzle ring of FIG. 1.

FIG. 8 is a detailed front perspective view of one of a
plurality of nozzle vanes for the nozzle ring of FIG. 1.

FIG. 9 is a detailed front view of one of the plurality of
nozzle vanes for the nozzle ring of FIG. 1.

FIG. 10 is a detailed back view of one of the plurality of
nozzle vanes for the nozzle ring of FIG. 1

FIG. 11 is a detailed left side view of one of the plurality of
nozzle vanes for the nozzle ring of FIG. 1

FIG. 12 is a detailed right side view of one of the plurality
of nozzle vanes for the nozzle ring of FIG. 1

FIG. 13 is a detailed top view of one of the plurality of
nozzle vanes for the nozzle ring of FIG. 1; and,

FIG. 14 is a detailed bottom view of one of the plurality of
nozzle vanes for the nozzle ring of FIG. 1.

The solid lines in FIGS. 1-7 illustrate a nozzle ring for a
turbocharger according to the present disclosure. Specifi-
cally, FIGS. 1-7 illustrate the nozzle ring where the edges
along the circumference of the nozzle ring (e.g., as looking
at the nozzle ring from the perspectives of any of FIGS. 2-5)
are solid and no apertures are present. FIGS. 8-14 show
magnified and detailed views of one of a plurality of nozzle
vanes of the nozzle ring.
